UNITED STATES PATENT OFFICE.

PERCY H. DONHAM, OF SULLIVAN, INDIANA.

REFRIGERATOR.

Application filed October 11, 1923. Serial No. 667,970.

To all whom it may concern:

Be it known that I, PERCY H. DONHAM, a citizen of the United States, residing at Sullivan, in the county of Sullivan and State of Indiana, have invented certain new and useful Improvements in Refrigerators; and I do declare the following to be a full, clear, and exact description of the invention, such as will enable others skilled in the art 10 to which it appertains to make and use the same.

It is the object of my invention to provide an improved type of refrigerator, in which the ice chamber is located in the upper portion 15 of the casing, and novel provision is made for insuring a circulation of air from said ice chamber to the refrigerating chamber below and vice versa.

With the foregoing in view, the invention 20 resides in the novel subject matter herein-after described and claimed, the description being supplemented by the accompanying drawing.

Figures 1 and 2 are vertical sectional views looking in different directions, each view indicating the plane upon which the other view is cut, by means of the lines 1—1 and 2—2.

Figure 3 is a horizontal sectional view on 30 the irregular line 3—3 of Fig. 1.

I have shown a refrigerator casing comprising a front wall 1 having a door 2 in its lower portion, a rear wall 3, a pair of side walls 4, a bottom 5, and a top 6 having an ice door 7. While none of these walls have been shown of insulated form, it will be understood that all of them may be of any desired heat insulating construction.

Spaced inwardly from the side walls 4 a suitable distance to provide upright air passages 8, are two curtain walls 9, said walls extending from front to back of the casing and from the top 6 of the latter to points spaced from the bottom 5. Within the upper portion of the casing, is an ice chamber bottom 10 which likewise extends from front to back of said casing, but has its ends in spaced relation with the curtain walls 9. Ice chamber end walls 11 rise from the ends 50 of the bottom 10 and have their upper edges spaced downwardly from the top 6, said walls 11 being extended from front to back

of the casing. Suitable air passages 12 extend through the lower portions of the walls 11, across the spaces 13 between the latter 55 and the curtain walls 9, and through said curtain walls, for communication with the air passages 8, a suitable number of said passages being located at each end of the ice chamber. Any desired drip outlet may 60 be provided for the ice chamber.

By the construction described, cold air from the ice chamber will pass outwardly through the passages 12, then downwardly 65 through the passages 8, and will enter the lower refrigerating compartment by turning under the curtain walls 9. The warmer air within this compartment, ascends, escapes through the passages 13, and thus again comes in contact with the ice, so that it is 70 effectively chilled. A steady circulation of air is thus produced at opposite sides of the refrigerator, which greatly increases the efficiency of the latter.

The construction intended is exceptionally 75 simple and inexpensive, yet it will greatly increase the efficiency of any refrigerator. The general structure disclosed may be followed if desired, but within the scope of the invention as claimed, numerous minor 80 changes may be made.

I claim:

A refrigerator comprising a casing, a pair of curtain walls spaced inwardly from two opposed side walls thereof and extending 85 from front to back of said casing, said curtain walls also extending from the top of the casing to points spaced from its bottom, an ice chamber bottom in the upper portion of the casing extending from front to back 90 thereof and terminating in spaced relation with said curtain walls, ice chamber end walls rising from said ice chamber bottom and extending from front to back of the casing, said end walls being inwardly spaced 95 from said curtain walls and downwardly spaced from the casing top, and cold air outlet passages extending through the lower portions of said end walls, across the space between the latter and said curtain walls, 100 and through the latter.

In testimony whereof I have hereunto affixed my signature.

PERCY H. DONHAM.
